UNITED STATES PATENT OFFICE.

ISABELLA KERBY, OF EAST HELENA, MONTANA.

DESIGN FOR A PIG DOLL.

61,198.

Specification for Design.

Patented July 11, 1922.

Application filed February 20, 1922. Serial No. 796. Term of patent 7 years.

To all whom it may concern:

Be it known that I, ISABELLA KERBY, a citizen of the United States, residing at East Helena, in the county of Lewis and Clark and State of Montana, have invented a new, original, and ornamental Design for a Pig Doll, of which the following is a specification, reference being had to the accompanying drawing, forming part thereof.

Fig. 1, is a front view of a pig doll, illustrating my new design, and Fig. 2 is a rear view.

I claim:

The ornamental design for a pig doll as shown.

ISABELLA KERBY.
